HOOK FOR TOWELS OR THE LIKE

Guy Vrignaud, Grenoble, France, assignor to Allibert
Exploitation Societe Anonyme, Puteaux, France

Filed Nov. 6, 1974, Ser. No. 521,485

Term of patent 14 years

Int. Cl. D6—06

U.S. Cl. D6—102

FIG. 1

FIG. 2

FIG. 3

FIG. 4

FIG. 5

FIG. 6

FIG. 1 is a perspective view of a hook for towels or the like showing my new design;

FIG. 2 is a front elevational view thereof;

FIG. 3 is an end elevational view thereof, the other end elevational view being identical;

FIG. 4 is a rear elevational view thereof;

FIG. 5 is a top plan view thereof; and

FIG. 6 is a bottom plan view thereof.

I claim:

The ornamental design for a hook for towels or the like, as shown and described.
